WIRE CONNECTER

Lewis H. Church, Westfield, N. J., assignor to
 The Thomas & Betts Co., Elizabeth, N. J., a
 corporation of New Jersey

Application October 26, 1934, Serial No. 750,087

4 Claims. (Cl. 173—303)

The invention relates to a wire connector which is adapted to be secured to a wire and particularly to secure the end of a wire to some other structure, or to secure the ends of two wires in order to couple them together. The invention has particular applicability to hollow high tension wire built up of segmental interlocking strips. Such high tension wires may have a diameter between one and two inches and be stretched between towers quite widely spaced so that the connector is subjected to a heavy strain in supporting a considerable weight of cable or wire.

Sometimes the weight of the cable or wire is increased by the formation of ice thereupon in the winter, and a connector must be able to withstand this added strain caused by the increased weight supported thereby. Such connectors, in addition to withstanding the heavy strains to which they are subjected, must also be capable of withstanding this strain irrespective of the effect of varying temperature changes which may expand the parts of the connector unevenly and may tend to unloosen them. In other words, the connector must not become unloosened, which might occur due to different coefficients of expansion and contraction of the parts thereof under the changing temperatures to which connectors are exposed.

It is one of the principal objects of the invention to devise a wire connector which will be retightened, in case it should become unloosened for any reason, by the tension or pull exerted thereupon by the weight of the wire supported by the connector, and which result is accomplished with a minimum number of parts for the connector.

Another main object is to devise a wire connector which will aid in keeping the connector tightly gripping the wire and also retighten the same by the pull on the wire in case it should become unloosened, and which wire connector does not carry any operating means for initially tightening the connector. In this construction a hammer or separate means may be used to produce initial tightening of the connector, or it may be produced by the pull exerted by the wire when two connectors are fastened or coupled together.

Another fundamental object is to devise a wire connector in which one of the parts thereof extends beyond the end of the internal conical surface provided upon one of the parts of the wire clamping means and engages or contacts the wire in order to reduce or dampen vibration of the

wire and to prevent scoring of the wire by the end of the contractile sleeve.

Another object is to extend particularly the contractile sleeve so that it projects beyond the end of the internal conical surface of the clamping means and also projects beyond the end of a plug, if one is provided, in order to dampen vibration of the wire and particularly to prevent scoring of the wire by the end of the contractile sleeve.

Another broad object of the invention is to construct a wire connector having a retightening characteristic and in which the initial tightening of the connector is augmented by the pull of the wires as two connectors are drawn towards each other in coupling the ends of two wires together.

The broad objects of the invention have been outlined above and other objects can be stated which comprise various combinations of the principal objects set forth. Such other objects of the invention will be more apparent from the following description and claims taken in connection with the accompanying drawings illustrating some preferred embodiments of the invention, in which:

Figure 1 is an exploded view of one form of wire connector in which no initial operating means is provided on the connector in order to initially grip the wire, and the parts of the connector are shown in section.

Figure 2 is a longitudinal section of the assembled wire connector of Figure 1 with the end of a hollow high tension wire secured therein.

Figure 3 is an end view of the assembled connector shown in Figure 2.

Figure 4 is a longitudinal section of a wire connector similar to that shown in Figure 2, but which differs therefrom in having the contractile clamping sleeve projecting beyond the end of the supporting part.

Figure 5 is an end view of the connector of Figure 4.

Figure 6 is an exploded view of a wire connector adapted to couple the ends of two wires together, and having the contractile sleeve extending beyond the internal conical surface and the end of the plug.

Figure 7 is an assembled longitudinal section of the wire connector of Figure 6 after the connector has been initially contracted on the wire.

Figure 8 is a longitudinal section showing the wire connector of Figure 7 after it has been retightened by a pull on the wire.

Figure 9 shows an enlarged end view of the

wire and the interlocking connection between the segments forming the hollow wire.

Figure 10 is a longitudinal section through a wire connector which is initially tightened by an external means or by the pull of the wire when two connectors are drawn together, in order to provide a coupling for the ends of two wires. The two wire connectors are shown preparatory to drawing them together by a coupling member 10 or means.

Figure 11 is a longitudinal section through the wire connector of Figure 10 with the two connectors drawn completely into the coupler member during which process the connectors have become initially contracted.

The wire connector to be described herein is devised to provide as simple a structure as possible for securing the ends of high tension wire to some other structure or to the end of another wire. The connector, even though of simple construction, will support the heavy strain to which it will be subjected in service and has the characteristic of retightening itself in case it should become unloosened for any reason, such as uneven expansion or contraction of different parts thereof or brought about by varying temperatures to which the connector is subjected.

The connector shown in exploded view in Figure 1 consists of a means 10 having an internal 30 taper or conical surface 11. The means 10 carries screw threads 12, shown particularly on the exterior thereof, the purpose of which will be disclosed hereinafter. The means 10 may also carry flat portions or a hexagonal portion 13 to 35 enable the means to be held with a wrench. A contractile sleeve or means 15 has an external taper or conical surface 16 corresponding with the internal conical surface 11 of the means 10. The sleeve 15 is rendered contractile by a longitudinal slot 17 extending through the length of the contractile sleeve. Other means of rendering the sleeve contractile may be used. The bore 18 of the contractile sleeve 15 is preferably provided with biting ridges or teeth 19 which are heaviest 40 and deepest at the thick end of the sleeve and gradually taper off to a smooth surface at the smaller end of the sleeve. Preferably too the bore 18 is slightly smaller in diameter at the thicker end so that the inner end of the connector 45 carries a greater part of the clamping action on the wire than the thinner end of the sleeve.

A plug 22 which is shown as being hollow, although a solid plug may be utilized, has a diameter approximately that of the hole through 50 the hollow wire W so that it is insertable therein. The plug carries an outwardly extending flange 23 preferably at the end thereof. The purpose of the flange will be described hereinafter. The other end of the plug carries a taper 24 which aids 55 in inserting this plug within the hollow high tension wire. The plug 22 may also be provided with biting ridges or teeth 25 which are both more numerous and greater adjacent the flange 23 and taper off gradually towards the tapered end 24 60 of the plug.

A securing lug 28 is provided with internal threads 29 for engagement with the threads 12 on the connector means 10. Any other means may be used to secure the lug 28 to the internal conical surface means 10. The securing lug carries a flat extension 30 having an opening 31 therein for receiving a bolt or other anchorage means by which the connector is secured to some supporting structure.

In assembling the connector described, the

means 10 with the contractile sleeve 15 inserted therein is slipped over the end of the wire W until the end of the wire is adjacent to or at the inner end of the contractile sleeve 15. The plug 22 is then inserted within the end of the wire until the flange 22 engages the end of the contractile sleeve 15. The end of the plug may then be struck with a hammer in order to drive the plug and contractile sleeve into the means 10 so that the cooperating conical surfaces 11 and 16 on the means 10 and the contractile sleeve 15 forcibly contract the sleeve to grip the wire between the sleeve and the plug. Any other means separate from and independent of the connector may be utilized to enforce this axial movement between the contractile sleeve 15 and the means 10, whereby the tapers or conical surfaces cooperate to contract the contractile sleeve 15 and initially grip the wire. The lug 28 is then threaded upon the threads 12 of the means 10 to provide means for securing the connector and the wire to some other structure.

The contractile sleeve 15 is positioned upon the wire so that the small end thereof is spaced from the end of the wire and the large end thereof is adjacent to the end of the wire. The contractile sleeve therefore is in a retightening position as will appear more fully hereinafter. When the contractile sleeve 15 is contracted, the wire W, which has a certain degree of flexibility, is contracted slightly therewith so that the wire W, the contractile sleeve, and the plug 22 are clamped together as a unit through this clamping action. The biting ridges or teeth 19 in the bore 18 of the contractile sleeve 15 and the biting teeth 25 on the external surface of the plug 22 dig into the wire and firmly fix or anchor the contractile sleeve and the plug 15 to the wire so that these three parts move together by the pull on the wire in case the connector should become unloosened due to changing temperatures, whereupon the contractile sleeve 15 is pulled axially with respect to the internal conical surface 11 to retighten the connector.

The retightening characteristic or feature of the connector is principally obtained by the flange 23 carried by the plug or plug means 22. The flange abuts the end of the contractile sleeve 15. The plug 22 is freely movable with the wire W in order to retighten the connector if it should become unloosened. If unloosening should occur and the wire tends to pull out of the connector, the plug 22 moves with the wire W and the flange 23 engaging the end of the contractile sleeve 15 forces the contractile sleeve axially with respect to the means 10 and the internal conical surface 11 thereon to assure positive retightening of the connector. The flange 23 therefore is one of the means cooperating between the plug 22 and the contractile sleeve 15 for retightening the connector.

The flange 23, particularly shown as being carried by the plug 22, provides means carried by the plug which engages a shoulder 38 formed by the end of the contractile sleeve 15 which is spaced from the small end of the contractile sleeve. The means carried by the plug 22 for engaging the shoulder 38 on the contractile sleeve 15 need not be a flange 23 nor does the shoulder carried by the contractile sleeve 15 need be the shoulder 70 formed by the end of the contractile sleeve. The flange 23 and shoulder 38 together form means cooperating between the plug 22 and the contractile sleeve 15 to retighten the connector by the pull on the cable in case it should become 75

unloosened. In the construction shown in Figures 1 to 5 inclusive, a hammer or other external and separate initial tightening means is utilized in order to initially secure the end of the wire W within the connector, and the connector is provided with a second operating means for retightening the connector by the pull on the wire in case it should become unloosened when in use. The second operating means cooperates with the contractile sleeve to force the latter axially within the means 10. In other words, the connector described is capable of being retightened by the pull on the wire in case it becomes unloosened and consists of only three essential parts, namely a means having an internal conical surface which means is adapted to be secured to some other structure, a contractile sleeve positioned upon the wire, as shown and described, and a plug insertable within the wire and having means cooperating with the contractile sleeve to retighten the connector by the pull on the wire. The means 10 is shown as extending substantially beyond the end of the contractile sleeve 15 and the end of the plug 22, which extension engages the wire W. This extension of the connector means 10 tends to prevent vertical oscillation of the wire and also resists abrasion at the end of the contractile sleeve which may cause subsequent fracture of the wire. Such an extension provides means engaging the wire beyond the end of the internal conical surface.

Figure 4 shows another form of construction quite similar to that shown in Figures 1 and 2. In this construction the anchorage means or securing lug 28 is threadedly secured to the means 35 which carries an internal taper 36. A contractile sleeve 37 is adapted to fit over the wire W with its smaller end spaced from the end of the wire and its larger end adjacent to the end of the wire, so that it is in a position to be retightened by the pull on the wire in case it should become unloosened. The construction of Figure 4 differs from that of Figures 1 and 2 in the contractile sleeve 37 projecting beyond the end of the means 35 and engaging the wire W at a point beyond the end of the internal conical surface 36, instead of having the means 35 perform this function. The means 35 in Figure 4 is consequently shorter than the corresponding means 10 of Figure 2.

The projecting end of the contractile sleeve 37 provides a flexible end therefor which is unsupported by any exterior part. The swaying of the wire W is tended to be damped by the projecting end of the contractile sleeve, and also the contractile sleeve provides no rigid or rigidly supported corner to score the wire when it vibrates or sways and thereby eventually produce a weakened wire. The end of the projecting contractile sleeve extends to a substantially sharp edge so that this end is not rigid, but has a certain degree of flexibility. The connectors of Figures 1 through 4 show therefore that one of the parts of the connector extends beyond the end of the internal conical surface and engages the wire to prevent scoring of the wire by the contractile sleeve and to tend to prevent vibrations or the undesirable effects of vibrations of the wire W.

The plug 22 of Figures 1 and 2 may be inserted into the wire W, which plug may be provided with the flange 23. The flange 23 provides means carried by the plug which engages an axial shoulder 38 formed by the end of the contractile sleeve for retightening the contractile sleeve in case it should become unloosened. It will be noted too,

that the contractile sleeve 37 projects beyond the end of the plug 22 and projects well beyond the point where the tapered end of the plug begins, which is the innermost point of the wire which contacts with the plug, so that the flexibility of the end of the contractile sleeve is not affected either by the plug 22 or the means 35.

Although the construction shown in Figure 4 shows the use of a plug 22 inserted within the end of the wire, which plug carries a flange, it will be understood that the combination disclosed in this view may be utilized on solid wires and may be utilized on hollow wires without the use of a plug. The improvement fundamentally lies in one of the parts, and particularly the contractile sleeve 37, projecting beyond the internal conical surface to prevent scoring of the wire W.

Figures 6 through 8 show a wire connector constructed much like the connector shown in the Buchanan application 688,560. This connector 20 has a body member 42 having an internal bore 43 and internal screw threads 44 at the end of the body member. An outer expansible sleeve 46 having an internal conical surface 47 is inserted within the bore 43 of the body member 42. The expansible sleeve 46 has a slot 48 to render this sleeve expansible. An inner contractile sleeve 50 has an outer conical surface 51 which engages the internal conical surface 47 on the outer expansible sleeve 46. The contractile sleeve 50 has a bore 52 within which a hollow wire W is received so that the contractile sleeve fits over the end of the wire W. The contractile sleeve 50 has a longitudinal slot 53 which renders the sleeve contractile.

An operating means or nut 55 has external screw threads 56 which cooperate with the internal threads 44 on the body member 42. The operating nut engages the large end of the outer expansible sleeve 46 and forces it into the body member so that the conical surfaces on the sleeves 46 and 50 forcibly engage to contract the contractile sleeve 50 and expand the expansible sleeve 46.

It will be observed that the operating nut 55, the expansible sleeve 46 and the body member 42 are combined into an integral or one piece element in the construction shown in Figures 1 through 4 and in Figures 10 and 11. These three parts in the form of construction shown in Figures 6 through 8, therefore, together form means having an internal conical surface. Because this means in Figures 6 through 8 also includes the operating nut 55, as well as the expansible sleeve 46, this construction provides means carried by the connector which is capable of another function, namely the function of initially contracting the contractile sleeve 50 by causing relative movement to occur between the internal conical surface 47 and the contractile sleeve 50. Any initial operating means whatever is contemplated by the invention which has the function of producing relative movement between an internal conical surface, such as the surface 47, and the contractile sleeve 50. Such operating means may or may not be carried by the connector.

The operating nut 55 is preferably provided with a bore 57 so that the wire has ample room to vibrate therein and so that the flexible end of the contractile sleeve 50 is unsupported beyond the end of the internal conical surface 47. The operating nut 55 may engage the wire W, as described in the Buchanan Patent 2,056,248, so long

as it does not support the free end of the contractile sleeve 50.

The expansible sleeve 46 upon being forced into the body member 42 expands as the contractile sleeve 50 contracts, so that the expansible sleeve expands into firm engagement with the bore 43 of the body member 42. This firm engagement between these two parts assures better electrical contact through the connector and 10 also assists in resisting the pull of the wire so that the weight of the wire is not carried entirely by the screw threads of the operating nut 55. The expansible sleeve need not be expansible, if it is not desired to take advantage of the additional 15 function provided by it being expansible.

A plug or plug means 60 has a tapered end 61 to facilitate the insertion of the plug within the hollow wire. The plug 60 also has a flange 62 which engages an axial shoulder 54 spaced from 20 the smaller end of the contractile sleeve and formed by the larger end thereof. The flange provides means carried by the plug 60 for retightening the connector in case it should become unloosened by the pull of the wire. This 25 retightening characteristic is obtained in that the plug 60 is freely movable with the wire so that when the wire tends to pull out of the connector, the plug moves therewith and the flange 62 forces the contractile sleeve 50 to also move 30 with the wire, whereupon the contractile sleeve is further contracted to more firmly grip the wire.

In the construction shown in Figures 10 and 11, a wire connector, much like that shown in Figure 4, is illustrated. In this construction, however, the means 65 has right-hand screw threads 66, whereas the other means 70 has left-hand screw threads 71. The coupler means 74 has internal right-hand threads 75 and internal left-hand threads 76 to receive, respectively, the right-hand threads 66 on the means 65 and the left-hand threads 71 on the means 70. Upon rotating the coupler means 74, the means 65 and 70 and hence the wire connectors of which they 45 are a part, are drawn towards each other and in so being drawn towards each other, the pull on the wire will initially tighten the contractile means 37 so that no other initial operating means may be necessary. In order to assure, 50 however, that the wire is initially secured therein with a sufficient degree of security, each contractile sleeve 37 may be initially contracted by hitting the head or flange 23 of each plug 22 with a hammer.

It is understandable, of course, that the construction shown in Figures 10 and 11 may be used for solid wire, in which case of course a plug cannot be used, and may also be used with hollow wire without the use of a plug, if so desired. It 60 should also be noted that in the double ended connectors for securing the ends of two wires together, such as in the constructions shown in Figures 6 through 11, one of these wire connectors is broadly a means for securing the other connector to some other structure, which is also the purpose of the lug 30, shown in the construction in Figures 1 through 4. The biting ridges or teeth 19 and 25 shown on plug 22 and contractile sleeve 15 may be likewise provided on the same 65 parts in the other forms illustrated.

It has been found also that by making the bore 52 of the contractile sleeve 50 slightly tapered, so that the bore is slightly less in diameter at the large end of the contractile sleeve, that upon 70 contraction of the sleeve, a larger proportion of

the clamping stress is carried near the end of the wire. This result is understandable since with uniform contraction throughout the length of the sleeve, the smaller bore at the inner end of the contractile sleeve 50 would provide greater 5 gripping power at this end, since the bore 52 will at all times have a diameter less than the diameter at the other end of the bore. The purpose for tapering the bore 52 of the contractile sleeve is to so construct the sleeve that a smaller proportion of the total clamping strain on the wire is carried at the small end of the contractile sleeve where excessive strains are more likely to fracture the wire.

Various modifications will occur to those skilled 15 in the art in the configuration, composition and disposition of the component elements going to make up the invention as a whole, as well as in the selective combination or application of the respective elements, and no limitation is intended 20 by the phraseology of the foregoing description or illustrations in the accompanying drawings.

What is claimed is:

1. A wire connector comprising means having an internal conical surface, a contractile sleeve 25 adapted to fit over the wire and having an exterior conical surface engaging the internal conical surface, the contractile sleeve having its smaller end spaced from the end of the wire and its larger end adjacent to the end of the wire, 30 the contractile sleeve having a flexible end extending substantially outwardly and engaging the wire beyond the end of the internal conical surface to provide a yieldable support for the wire where it enters the connector, an operating nut 35 carried by the aforesaid means for initially contracting said contractile sleeve to grip the wire by enforcing relative movement between the contractile sleeve and the internal conical surface, and the operating nut extending outwardly beyond the contractile sleeve and adapted to engage the wire.

2. A wire connector for hollow wire comprising means having an internal conical surface, a contractile sleeve adapted to fit over the wire 45 and having an exterior conical surface engaging the internal conical surface, the contractile sleeve having its smaller end spaced from the end of the wire and its larger end adjacent to the end of the wire, plug means insertable within the 50 wire, means carried by the plug means and cooperating with the contractile sleeve to retighten the connector in case it should become unloosened, the contractile sleeve having a flexible end extending outwardly and engaging the wire beyond the end of the internal conical surface and the end of the plug means where it engages the inner surface of the wire to provide a yieldable support for the wire where it enters the connector, an operating nut to initially contract said 60 contractile sleeve to grip the wire by enforcing relative movement between the contractile sleeve and the internal conical surface, and the operating nut extending outwardly beyond the contractile sleeve and plug means and adapted to engage the wire to further protect the wire against 65 scoring.

3. A self-tightening wire connector for connecting the end of a hollow wire comprising a connector sleeve having an internal conical surface the smaller diameter of which is spaced from and the larger diameter of which is located adjacent to the end of the wire, the connector sleeve having an open front end through which the wire is adapted to be projected and an open 70 75

- 5 rear end, a contractile sleeve adapted to fit over the wire and having an external conical surface engaging the inner conical surface of the connector sleeve with its smaller end spaced from and its larger end located adjacent to the end of the wire, a plug insertable within the end of the wire, means carried by the plug and the contractile sleeve cooperating together to move the latter axially relatively to the connector sleeve
- 10 5 when an external force is applied at the large diameter end of the contractile sleeve through the open rear end of the connector sleeve for initially tightening the said contractile sleeve against the wire and plug and also for retightening the contractile sleeve by the pull on the wire, and means on said connector sleeve for securing the latter to some other structure.
- 15 4. A self-tightening wire connector for connecting the end of a hollow wire comprising a connector sleeve having an internal conical surface the smaller diameter of which is spaced from and the larger diameter of which is located adjacent to the end of the wire, the connector sleeve having an open front end through which

the wire is adapted to be projected and an open rear end, a contractile sleeve adapted to fit over the wire and having an external conical surface engaging the inner conical surface of the connector sleeve with its smaller end spaced from and its larger end located adjacent to the end of the wire, a plug insertable within the end of the wire, means carried by the plug and the contractile sleeve cooperating together to move the latter axially relatively to the connector sleeve 10 when an external force is applied at the large diameter end of the contractile sleeve through the open rear end of the connector sleeve for initially tightening the said contractile sleeve against the wire and plug and also for retightening the contractile sleeve by the pull on the wire, means on said connector sleeve for securing the latter to some other structure, and means operating through the open rear end of the connector sleeve to initially force the contractile sleeve relatively to the connector sleeve to initially tighten the wire connector.

LEWIS H. CHURCH.
